RADIAL ENGINE CRANKSHAFT MECHANISM

Robert D. Willis, Del Rio, Tex.

Application July 28, 1950, Serial No. 176,468

2 Claims. (Cl. 74—52)

1

The present invention relates to a radial engine crank shaft mechanism and it consists in the combinations, constructions and arrangements of parts herein described and claimed.

Generally there is provided a radial engine crank shaft mechanism including an engine casting from which extends a plurality of cylinders in each of which is reciprocally mounted a piston. A crank shaft extends centrally through the casting and is provided with a crank pin upon which is revolvably mounted a circular link rod hub, the periphery of which is interconnected by piston rods with the various pistons and to which is affixed a gear. A counterweighted plate extends outwardly from one side of the crank shaft and is provided at either side with a stub shaft which extends therethrough and each of which is provided with a planetary gear at either end thereof. The planetary gears at one side of the plate are enmeshed with the gear attached to the hub and the planetary gears at the other side of the plate are enmeshed with a gear which is identical with the gear attached to the hub and which is formed integrally with a worm wheel which is, in turn, enmeshed with a transversely extending worm mounted upon the inner side of the casing. A pin anchored to the inner side of the casing extends through an arcuate slot formed in the worm wheel. Revolution of the worm acts to change the timing of the conventional firing within the cylinders.

It is accordingly an object of the invention to provide a mechanism of the character set forth which is comparatively simple and inexpensive and yet which is effective and efficient in use.

Another object of the invention is the provision of novel means, in a mechanism of the character set forth, for altering the timing arrangement of an engine with which it may be utilized.

A further object of the invention is the provision, in a mechanism of the character set forth, of a novel crank connection for the piston rods of a radial engine.

A still further object of the invention is the provision, in a mechanism of the character set forth, of novel gearing forming a part of the invention.

A still further object of the invention is the provision, in a mechanism of the character set forth, of novel means for regulating the same.

Other and further objects of the invention will become apparent from a reading of the following specification taken in conjunction with the drawings, in which:

2

Figure 1 is a fragmentary vertical sectional view, partly in elevation, of an engine embodying the present invention.

Figure 2 is an enlarged sectional view, partly broken away, taken along line 2—2 of Figure 1.

Figure 3 is a fragmentary sectional view taken along line 3—3 of Figure 2.

Figure 4 is a fragmentary sectional view taken along line 4—4 of Figure 3.

Figure 5 is a fragmentary elevational view, partly in section, illustrating a worm wheel, worm and associated parts forming a part of the invention.

Figure 6 is an enlarged fragmentary sectional view taken along line 6—6 of Figure 3.

Figure 7 is a fragmentary sectional view taken along line 7—7 of Figure 6.

Figure 8 is an exploded perspective view of a pair of planetary gears utilized in the invention.

Figure 9 is a perspective view of a bushing utilized in connection with the planetary gears shown in Figure 8, and

Figure 10 is a perspective view of a pin or stub shaft utilized in connection with the device shown in Figures 8 and 9.

Referring more particularly to the drawings, there is shown therein a radial engine crank shaft mechanism comprising a casing 10 having outwardly extending therefrom a plurality of cylinders 11 in each of which is reciprocally mounted a piston 12. Centrally extending through the casing 10 and journaled in stub bushings 13 and 14 is a crank shaft 15 to which is affixed a plate or cheek 16 having a crank 17 affixed thereto at one of its ends and having a crank arm 18 keyed, as indicated at 19 to its other end and a tapered fitting, a nut 20 serves to maintain the arm 18 in keyed condition upon the crank 17.

A link rod hub 21 is revolvably mounted upon the crank 17 and has pivotally connected thereto at its periphery, as indicated at 22, a series of link rods 23 each of which is pivotally connected at its other end, as indicated at 24, to one of the pistons 12.

Affixed to one side of the hub 21 and surrounding the crank 17 is an annular gear 25 which is enmeshed with a pair of planetary gears 26 which are connected by skirt members 27 and skirt members 28 with a pair of like planetary gears 29. The skirt members 27 and 28 are keyed, as indicated at 30 and 31 in Figure 8 of the drawings, and extend through bushings 32 which extend transversely through either side of the cheek 16. Pins 33 extend through the interiors of the pairs of gears 26 and 29.

The gears 29 are, in turn, enmeshed with an annular gear 34 which surrounds the shaft 15 and which is integrally interconnected with a worm wheel 35 which likewise surrounds the shaft 15 and which is provided with an arcuate slot 37 through which extends a stub pin 38 which is anchored, as indicated at 39, to the inner wall of the casing 10.

Transversely and revolvably mounted in a pair of brackets 40 affixed to the inner wall of the casing 10 is a worm gear 41 which is provided with a control shaft 42. The gear 41 is enmeshed with the worm wheel 35. The outer surfaces of the skirt members 27 and 28 are preferably finished with a high polish to act as bearings when they are mounted within the bushings 32 and pins 33 are preferably press-fitted into the bores of the gears 26 and 29. The cheek 16 is provided with a counterweight 43.

In operation, it will be apparent that when the engine is in operation the pistons 12 will reciprocate in timed relation to one another within their respective cylinders 11. This action will cause the conventional rotary movement of the crank pin 17 through the rods 23 and the hub 21. It will be noted, however, that the movement of the hub 21 with respect to the shaft 15 is not only planetary but that any particular point upon the periphery of the hub 21 will remain at all times in its same relative position, that is to say the uppermost position along the periphery of the hub 21 will remain uppermost regardless of the position of the hub 21 with respect to the shaft 15. This fact makes for a lessening in the oscillatory movements of the rods 23 from that conventionally incurred thus lessening wear upon the various bearings causing the lengthening of the useful life of such bearings.

Since the worm wheel and its attached gear 34 are normally at a standstill due to the fact that the worm wheel is enmeshed with the worm 41, it will be seen that the planetary gears 26 and 29 will cause the motion of the hub 21 as above described and that if no further movement is given the worm wheel 35 that firing within the cylinders 11 will take place identically with each revolution of the engine. When, however, it is desired to alter the timing of the engine, it is only necessary to revolve the worm gear through its control shaft 42 thus moving all of the pivot points 22 in a counterclockwise or clockwise direction as the case may be thus speeding up or retarding the timing of the engine. It will be apparent that the length of the slot 27 will act to limit the movement of the worm wheel 35 due to the fact that the stub pin 38 extends laterally therethrough. It will also be seen that the control shaft 41 may be turned manually, electrically, mechanically or otherwise as the contingency may direct.

While but one form of the invention has been shown and described herein, it will be readily apparent to those skilled in the art that many minor modifications may be made without departing from the spirit of the invention or the scope of the appended claims.

What is claimed is:

1. A mechanism of the character described for use in connection with a radial engine having a casing, cylinders, and pistons in said cylinders; the provision of a crankshaft extending centrally through said casing, a crank pin for said crankshaft in said casing, cheeks interconnecting said crank pin and said crankshaft, one of said cheeks being in the form of a plate, a link rod hub rev-

olably mounted on said crank pin, piston rods pivotally connected with said hub at their inner ends and pivotally connected at their outer ends with said pistons, an annular gear affixed to said hub and surrounding said crank pin, a second annular gear of equal size to said first-mentioned annular gear surrounding said crankshaft, driving interconnection between said annular gears carried by said plate-like cheek, means for selectively and circumferentially positioning the annular gear carried by said crankshaft, and means for limiting the movement of said last-mentioned annular gear, said positioning means including a worm wheel surrounding said crankshaft and affixed to the last-mentioned annular gear, a worm gear affixed to the inner wall of said casing and enmeshed with said worm wheel, and an operating shaft connected with said worm gear, said last-mentioned means including an arcuate slot formed in said worm wheel and a pin anchored in said casing and extending through said slot.

2. A mechanism of the character described for use in connection with a radial engine having a casing, cylinders, and pistons in said cylinders; the provision of a crankshaft extending centrally through said casing, a crank pin for said crankshaft in said casing, cheeks interconnecting said crank pin and said crankshaft, one of said cheeks being in the form of a plate, link rod hub revolvably mounted on said crank pin, piston rods pivotally connected with said hub at their inner ends and pivotally connected at their outer ends with said pistons, an annular gear affixed to said hub and surrounding said crank pin, a second annular gear of equal size to said first-mentioned annular gear surrounding said crankshaft, driving interconnection between said annular gears carried by said plate-like cheek, means for selectively and circumferentially positioning the annular gear carried by said crankshaft, and means for limiting the movement of said last-mentioned annular gear, a worm gear affixed to the inner wall of said casing and enmeshed with said worm wheel, and an operating shaft connected with said worm gear, said last-mentioned means including an arcuate slot formed in said worm wheel and a pin anchored in said casing and extending through said slot, and said driving interconnection comprising a pin extending through each side of said plate-like cheek, a first planetary gear carried at one end of each of said pins and enmeshed with the first-mentioned annular gear, and a second planetary gear carried at the other end of each of said pins and enmeshed with the other of said annular gears.
